STEEL RETAINER

Filed April 7, 1927

UNITED STATES PATENT OFFICE.

JOHN F. MOCK, OF PHILLIPSBURG, NEW JERSEY, ASSIGNOR TO INGERSOLL-RAND COMPANY, OF JERSEY CITY, NEW JERSEY, A CORPORATION OF NEW JERSEY.

STEEL RETAINER.

Application filed April 7, 1927. Serial No. 181,732.

This invention relates to rock drills, but more particularly to steel retainers for rock drills of the hammer type.

The objects of the invention are to prevent ejection of the working implement from the drill and to enable the retainer to be quickly attached to the drill and removed therefrom.

Other objects will appear hereinafter, and to all of these ends the invention consists of the combination of elements and arrangement of parts having the general mode of operation substantially as hereinafter described and claimed and illustrated in the accompanying drawings, in which

Figure 1 is a vertical sectional view of a front end of a rock drill having the invention applied thereto,

Figure 2 is a vertical side view partly broken away, and

Figure 3 is a view of the front end of the drill.

Referring more particularly to the drawings, A designates a cylinder, only a portion of which is shown. A front cylinder washer B forms a closure for the front end of the cylinder and is bored to receive slidably a piston C reciprocable in the cylinder A. At the front end of the cylinder A is disposed a front head D having lugs E through which extend side bolts F whereby the front head may be secured to the cylinder.

The front head D is preferably provided with a bushing E' having a rearward cylindrical bore F' and a forward bore G. The bore G may be of any suitable form to receive the shank of a working implement H.

The working implement H in this instance has a collar J which cooperates with the front end of the bushing E' to limit the distance which the shank of the working implement may extend into the bore G. An additional function of the collar J is to prevent ejection of the implement H from the front head, as will be described more fully hereinafter.

Near the front end of the front head D and at one side thereof is formed a lug K having a longitudinal slot L which opens into a transverse slot O also in the lug K. The slot L is intended to act as a guide for an arm P of a retainer Q. The retainer Q in this instance is disposed at an angle to the arm P and has an aperture R to receive the

working implement H. The aperture R in this instance comprises an enlarged portion S and a portion T of smaller area. The portion T of the aperture R is preferably only of such area as to permit the implement H to reciprocate freely therethrough.

The means for pivoting the retainer Q to the front head of the drill consists in this instance of a pin U which extends through the free end of the arm P and is adapted to lie in the transverse slot O in which it may reciprocate longitudinally of the front head.

Suitable means are provided for cushioning the impact of the working implement against the retainer Q. To that end the lug K is provided with apertures V on opposite sides of the slot L to act as guides for plungers W held against the pin U by means of springs X guided by the apertures V.

In order to prevent the retainer Q from rocking out of retaining position, or out of releasing position during the time the drill steel is being changed, the front head D is provided with a lug Y located rearwardly of the lug K and having an aperture Z for the reception of a plunger b adapted to bear against end surfaces c and d of the arm P. A spring e also disposed in the aperture Z acts on the plunger b to force the said plunger firmly against the surfaces c and d. By inclining the surface c from the surface d the plunger b may seat flatly on the surface c for holding the retainer in releasing position.

During the operation of the drill, the retainer Q will normally be held in the retaining position by the plunger b acting against the surface d. In this position of the retainer, whenever the working implement H is suddenly driven forwardly, the collar J may strike against the retainer Q and in this way the implement H is held against ejection from the drill. Whenever it is desired to change the working implement, the retainer Q may be rocked to the releasing position illustrated in dot and dash lines, thus moving the enlarged portion S of the aperture R into the path of the collar J and, since this portion of the aperture is of greater diameter than the collar J, the implement H may be freely withdrawn from the drill and another implement substituted therefor. After the insertion of another implement, the retainer Q may again be

rocked into its retaining position wherein it will be held securely by the plunger *b* under the influence of the spring *e*.

I claim:

5. 1. A steel retainer for a rock drill, comprising in combination with a front head and a collared working implement, a lug on the side of the front head having a longitudinal slot and a transverse slot, a retainer 25 encircling the implement forwardly of its collar to retain said implement in the front head, one arm integral with the retainer guided by the longitudinal slot, a pin in the 30 arm rotatable in the transverse slot to form a pivot for the retainer, said pin also being of the collar of said implement, an arm on the retainer guided by the longitudinal slot, a pin in the 35 end of the arm rotatable in the transverse slot, said pin also being slidable in said transverse slot longitudinally of the front head, plungers in the lug acting on the pin to support the retainer, 40 springs acting against the plungers to absorb the impact of the implement against the means including springs and plungers in the retainer, and a spring pressed plunger in the lug to cushion the impact of the implement against the retainer, and a spring pressed plunger in the front head pressing against the free end of the arm to hold the retainer in retaining and releasing positions.
10. 2. A steel retainer for a rock drill, com- 45

prising in combination with a front head and a collared working implement, a lug on the side of the front head having a longitudinal slot and a transverse slot, a retainer 25 encircling the implement forwardly of its collar to retain said implement in the front head, one arm integral with the retainer guided by the longitudinal slot, a pin in the 30 arm rotatable in the transverse slot to form a pivot for the retainer, said pin also being of the collar of said implement, an arm on the retainer guided by the longitudinal slot, a pin in the 35 end of the arm rotatable in the transverse slot, said pin also being slidable in said transverse slot longitudinally of the front head, plungers in the lug acting on the pin to support the retainer, 40 springs acting against the plungers to absorb the impact of the implement against the means including springs and plungers in the retainer, and a spring pressed plunger in the lug to cushion the impact of the implement against the retainer, and a spring pressed plunger in the front head pressing against the free end of the arm to hold the retainer in retaining and releasing positions.

In testimony whereof I have signed this specification.

JOHN F. MOCK.
